(57) **CLAIM**

(21) Appl. No.: **29/571,006**

The ornamental design for a “support pad of protective gear for body,” as shown and described.

(22) Filed: **Jul. 13, 2016**

DESCRIPTION

(51) **LOC (10) Cl.** **29-02**

FIG. 1 is a top front left perspective view of a support pad of protective gear for body showing my new design;

(52) **U.S. Cl.**

FIG. 2 is a front view thereof;

USPC **D29/122**

FIG. 3 is a rear view thereof;

(58) **Field of Classification Search**

FIG. 4 is a left side view thereof;

USPC D29/102–107, 122; 2/5, 6.1, 6.3, 6.7,
2/41–412, 414, 422–425, 9, 10; D2/869,

FIG. 5 is a right side view thereof;

D2/870, 872, 882, 884, 891

FIG. 6 is a top view thereof;

CPC A42B 3/00; A42B 3/127; F41H 1/08

FIG. 7 is a bottom view thereof;

See application file for complete search history.

(56) **References Cited**

FIG. 8 shows that the support pad of protective gear for body of our design is flexible and deforms as a specific shape according to the shape of the body which the support pad disposed on; and,

U.S. PATENT DOCUMENTS

FIG. 9 shows the support pad of protective gear for body of our design combines with the protective gear for body.
